UNITED STATES PATENT OFFICE.

ALBERT H. NEILSON, OF TULSA, OKLAHOMA.

SUCKER-ROD ELEVATOR.

Application filed May 12, 1926. Serial No. 108,551.

My invention relates to elevators used in oil well apparatus and more particularly to sucker rod elevators.

It is a purpose of my invention to provide a sucker rod elevator which can be engaged around the sucker rod by merely moving the same sidewise into position without the manual actuation of any means to unlock the locking members provided thereon.

10 It is a further purpose of my invention to provide a device of the above mentioned character that is provided with a pair of pivotally mounted jaw members for holding the sucker rod in position, said jaw members being angular and having portions that are normally arranged in converging relation so that movement of a sucker rod into the opening provided in the body portion of the elevator through the opening in one side

15 thereof which the jaws normally close, will separate the jaws to permit the rod to pass to final position in the elevator, and after said rod has passed to such position, the jaws will move to closing position. The

20 jaws are preferably so mounted that after the rod has reached its final position, any tendency of the same to move outwardly relative to the elevator will cause the jaws to move into firmer engagement with each.

25 other, thus automatically preventing the separation of the jaws when the rod tends to move out of the elevator but permitting separation thereof when the rod is moved into position in the elevator.

30 It is another purpose of my invention to provide angular, substantially L-shaped jaw members pivoted substantially at the junction of the legs of the jaws, one leg of each jaw extending outwardly in diverging relation away from the pivot and being provided with resilient means for moving the other legs of the jaws into engagement, said other legs of the jaws being then arranged in converging relation to each other and extending inwardly from the pivots away from the open end of the passage leading into the body portion of the elevator.

35 It is a further purpose of my invention to provide means for moving the jaws against the action of the resilient means into releasing position, comprising an angular actuating member and means interposed between the actuating member and the legs of the jaws having the resilient means in engagement therewith for moving said jaws against the action of the resilient means upon

swinging of the actuating member around its axis.

Other objects and advantages of the invention will appear as the description of the accompanying drawings proceeds. However, I do not wish to be understood as limiting myself to the exact details shown or described, but to include as part of my invention all such obvious changes and modifications of parts as would occur to a person skilled in this art and as fall within the scope of the claims.

In the drawings:

Fig. 1 is a perspective view of my improved elevator, showing a sucker rod in engagement therewith.

Fig. 2 is a similar view thereof, with the sucker rod removed, as viewed from the closed side thereof.

Fig. 3 is a perspective view of the jaw members and actuating means therefor, shown in separated relation.

Fig. 4 is a transverse, sectional view of the elevator with the jaws closed.

Fig. 5 is a similar view thereof with the jaws open.

Fig. 6 is a section taken substantially at right angles to Fig. 4, and

Fig. 7 is a perspective view of one of the jaw members.

Referring in detail to the drawings:

My improved elevator comprises a body portion 10 which is provided with an opening 11 extending through the same from one end to the other end thereof, said opening extending substantially at right angles to the axis of the pivot lugs 12 provided for pivoting the bail member 13 to the body portion 10. The body portion 10 is further provided with a passage 14 extending laterally from the opening 11, which is enlarged toward the outer end 15 thereof to provide for the ready passage of the sucker rod 16 through the same into the opening 11. The opening 11 is provided with a curved wall portion 17 against which the rod 16 may seat.

The body portion 10 is hollowed out to provide the chambers 18 on opposite sides of the passage 14, thus providing top and bottom wall portions 19 and 20 and an end wall 21 on said body portion 10 at opposite sides of the passage 14, said walls 19 and 20 being provided with obliquely extending portions 22 and substantially parallel portions 23 to define the passage 14 and the

flaring mouth 15 thereof. Mounted between the walls 19 and 20 in the openings 18 are the jaw members 24, said jaw members being mounted on the pivots 25 which are mounted in the wall portions 19 and 20 and extend between the same. Said jaw members are substantially L-shaped with the pivot openings thereof located substantially at the angle of the L and are thus provided with inwardly extending leg portions 26 which normally converge inwardly from the pivots 25 at an acute angle to each other so that the same engage to close the passage leading from the opening 11. The legs 26 of the jaws 24 are held in engagement by means of the compression springs 27 which engage in suitable recesses 28 provided in the wall portions 21 and in suitable recesses 30 provided in the legs 31 of the jaws 24, said legs diverging from each other away from the pivots 25 and away from the passage 14.

The corners of the jaws may be rounded at 32, 33 and 34, but are preferably slightly bevelled at 35 so as to provide engaging faces 25 for the jaws when the same are in engagement with each other.

Mounted in suitable passages 36 provided in the portion 10, are the pins 37, said pins engaging with the legs 31 of the jaws 24 at one end thereof and being engaged at the other end thereof by the arm 38 of the angular actuating member 39 which is pivotally mounted on the pivot member 40 extending between the laterally extending walls 41 on the body portion 10. Said actuating member 39 is provided with any suitable hand grip or handle portion 42 and if desired, the body portion 10 is provided with a ledge or flange 43 extending outwardly therefrom so that a grip can be obtained on the member 42 by engaging the hand with the ledge 43 and the handle portion 42, the handle portion 42 being moved downwardly when the hand grips both the portion 42 and the ledge 43. Any suitable grooves or other undulations 44 or 45 may be provided on the members 42 and 43 for preventing slippage of the hand thereon. A coiled compression spring 46 surrounds each of the pins 37 and engages with the arm 38 of the actuating member 39 so as to hold the same in an upright position, as shown in Fig. 6. The body portion 10 is provided with a projecting flange portion 47 which has a bevelled face 48 with which the correspondingly bevelled portion 49 adjacent the enlargement 50 on the sucker rod engages when the same is in position in the elevator.

It will be obvious that if the rod member is moved relative to the elevator toward the opening 11 from the entrance to the passage 14, the same will cause the jaws 26 to yield, permitting the passage of the sucker rod into position in the opening 11. However, 65 after the sucker rod has reached such posi-

tion, the tendency of the jaws will be to hold the same in position in the opening 11 and on the seat 48, as any engagement of the rod with the legs 26 of the jaws 24 will tend to swing the same into engagement with each other, the faces 51 of said jaws thus forming a part of the rod receiving socket and acting as stop members to prevent disengagement of the rod from the elevator. It will also be obvious that a downward movement of the handle 42 will cause the actuating member 39 to swing on its pivot so as to cause the arm 38 thereof to move the pins 37 lengthwise in the openings 36 and swing the jaws 24 around to the position shown in Fig. 5, when the passage 14 will be opened to permit the elevator to be removed from the rod.

What I claim and desire to secure by Letters Patent is:—

1. In an elevator of the character described, a body having a vertical opening forming a rod seat and a passage leading from said opening forming a receiving throat, a jaw member pivoted on the body at each side of the passage on a vertical axis, means yieldingly urging the jaw members to close the passage, and an actuating member pivoted on the body on a horizontal axis and connected with the jaws for shifting the jaws to open the passage.

2. In an elevator of the character described, a body having a vertical opening forming a rod seat and a passage leading from said opening forming a receiving throat, a jaw member pivoted on the body at each side of the passage on a vertical axis, means yieldingly urging the jaw members to close the passage, an actuating member pivoted on the body on a horizontal axis and connected with the jaws for shifting the jaws to open the passage, and means yieldingly restraining the actuating member.

3. In an elevator of the character described, a body having an opening forming a rod seat and a passage leading through the body from said opening to form a receiving throat, a pair of angular jaws pivotally mounted on said body at opposite sides of the passage, means yieldingly urging corresponding portions of the jaws into the passage, and actuating mechanism comprising an angular member pivotally mounted on the body and pins operable by said member to shift the jaws against the tension of said yielding means.

4. In an elevator of the character described, a body having an opening forming a rod seat and a passage leading through the body from said opening to form a receiving throat, a pair of angular jaws pivotally mounted on said body at opposite sides of the passage, means yieldingly urging corresponding portions of the jaws into the passage, actuating mechanism comprising

an angular member pivotally mounted on the body and pins operable by said member to shift the jaws against the tension of said yielding means, and means yieldingly restraining the actuating mechanism to permit the jaws to close the passage.

5. In an elevator of the character described, a chambered body having a vertical opening forming a rod seat and a passage leading from said opening forming a receiving throat, a pair of angular jaws pivoted on said body, springs engaging out-turned portions of the jaws to project back-turned portions thereof into the passage, an angular handle member pivoted on said body, and pins on a vertical portion of the handle member engageable with the out-turned portions of said jaws to rock the jaws when the handle member is rocked.

20. 6. In an elevator of the character described, a chambered body having a vertical opening forming a rod seat and a passage leading from said opening forming a receiving throat, a pair of angular jaws pivoted on said body, springs engaging out-turned portions of the jaws to project back-turned portions thereof into the passage, an angular handle member pivoted on said body, pins slidable in said body, operable by said handle member and operable on said jaws to rock the jaws, and yielding means restraining the handle member to normally operate the jaws to close the passage.

7. In an elevator of the character described, a body portion having an opening extending therethrough, a passage extending laterally from said opening through the wall of said body portion and means for closing said passage comprising a pair of jaws having legs extending at an angle to each other, pivots for said jaws on opposite sides of said passage, one leg of each of said jaws extending away from said pivots in diverging relation, resilient means engaging said legs to normally hold the other legs of said jaws in engagement with each other with said legs converging from said pivots, and means for moving said jaws out of engagement with each other against the action of said resilient means.

8. In an elevator of the character described, a body portion having an opening extending therethrough, a passage extending laterally from said opening through the wall of said body portion and means for closing said passage comprising a pair of jaws having legs extending at an angle to each other, pivots for said jaws on opposite sides of said passage, one leg of each of said jaws extending away from said pivots in diverging relation, resilient means engaging said legs to normally hold the other legs of said jaws in engagement with each other with said legs converging from said pivots, said last mentioned legs extending

inwardly away from the entrance to said passage from said pivots, and means for moving said jaws out of engagement with each other against the action of said resilient means, comprising an angular pivotally mounted actuating member and means mounted between one arm of said actuating member and said jaws to swing the same away from each other upon swinging said actuating member about its pivot.

9. In an elevator of the character described, a body portion having an opening extending therethrough, a passage extending laterally from said opening through the wall of said body portion and means for closing said passage comprising a pair of jaws having legs extending at an angle to each other, pivots for said jaws on opposite sides of said passage, one leg of each of said jaws extending away from said pivots in diverging relation, resilient means engaging said legs to normally hold the other legs of said jaws in engagement with each other with said legs converging from said pivots, said last mentioned legs extending inwardly away from the entrance to said passage from said pivots, comprising an angular pivotally mounted actuating member and means mounted between one arm of said actuating member and said jaws to swing the same away from each other upon swinging said actuating member about its pivot, said means having resilient members embracing the ends thereof adjacent said actuating member and engaging said actuating member to hold the same in upright position.

10. In an elevator of the character described, a body portion having an opening extending therethrough, a passage extending laterally from said opening through the wall of said body portion and means for closing said passage comprising a pair of jaws having legs extending at an angle to each other, pivots for said jaws on opposite sides of said passage, one leg of each of said jaws extending away from said pivots in diverging relation, resilient means engaging said legs to normally hold the other legs of said jaws in engagement with each other with said legs converging from said pivots, and means for moving said jaws out of engagement with each other against the action of said resilient means, comprising an angular pivotally mounted actuating member, pins slidably mounted in said body portion between the first mentioned legs of said jaws and one arm of said actuating member and resilient members embracing said pins and mounted between said body portion and said actuating member to hold the same upright.

In testimony whereof I affix my signature.

ALBERT H. NEILSON.
